United States Patent Office.

B. F. STURTEVANT, OF JAMAICA PLAIN, MASSACHUSETTS.

Letters Patent No. 100,239, dated February 22, 1870.

IMPROVEMENT IN PRESSURE-BLOWERS.

The Schedule referred to in these Letters Patent and making part of the same.

To all whom it may concern:

Be it known that I, B. F. STURTEVANT, of Jamaica Plain, in the county of Norfolk, and State of Massachusetts, have invented Improvements in Pressure-Blowers; and I do hereby declare that the following, taken in connection with the drawings which accompany and form part of this specification, is a description of my invention sufficient to enable those skilled in the art to practice it.

This invention consists in a peculiar form of case, which may be described as a scroll or spiral pipe, the cross-sections of which, on planes radiating from the center of the wheel-shaft, start from and terminate on parallel planes square or at right angles to the axis of the wheel, the scroll-pipe being open on its inner side about one third of its circumference, the said pipe decreasing uniformly in size of cross-section from the area of the delivery-pipe to the small end of the pipe, which must be of sufficient area to be wider at the opening of its circumference than the width of the blower-wheel at its periphery.

For small blowers, I make the case whole by casting or by brazing or soldering sheet metal together.

For blowers of medium size, I make the case in two parts, preferably cast and joined in the central plane of the blower passing midway between the planes before mentioned; and for large blowers, I make the case of segments of the scroll.

My invention further consists in the combination, with a case having therein a wheel in the peripheral shrouding of which the air-outlet is made by a series of suitable holes or openings, of screens of wire cloth or perforated material in or over the air-inlets of the blower to prevent passage into the blast-wheel of objects larger than can pass freely through the outlet-openings made in the said wheel.

My invention further consists in a peculiarity of detail by which the journals of the wheel-shaft are uniformly lubricated throughout their length, said peculiarity consisting in making between the box, which has capability for universal motion to a limited degree, and the bushing which is held by said box, a chamber communicating with an oil-reservoir, the bushing being pierced with holes along its length and the holes being plugged with leather or other porous material, through which the oil filters in passing to the journal surfaces.

And my invention consists further in certain other peculiarities of arrangement and combination which will be described and set forth in the description which follows, in which reference is had to the drawings, which show a pressure-blower embodying my invention.

In said drawings—

Figure 1 is a vertical section of my improved blower

taken in a plane passing through the axis of the fan-wheel shaft.

Figure 2 is a side elevation of said blower; and

Figure 3 is a plan thereof.

The case shown in the drawings is represented as cast in one piece.

The flat-surfaced rings *a a* are parallel to each other, and in planes at right angles to the axis of shaft *b*, and make seats that can be easily faced off to receive the side disk plates *c*, which are also faced where they join upon the rings *a a*.

The pipe, which is of a scroll or spiral form, is so made that it constantly increases in diameter and area from the line *z z*, fig. 2, to where it arrives at the full size of the outlet-pipe *d*, the scroll pipe being open near and around the fan-wheel periphery and its cross-sections ending upon the rings *a a*.

The disk plates *c* have large central openings which are bordered with T-shaped grooves seen at *e*, fig. 1, in which grooves fit the rings *f* of the spider arms *g*, which terminate in hubs *h*, which sustain the boxes *i* for the shaft journals *j*, and in said grooves are placed the heads of the bolts *k*, which hold the arms *g* in any desired angular position to accommodate each belt which passes over each side of an arm, *g*, on each side of the blower upon the driving pulleys *l*, there being preferably two, one at each side of the blower.

The rings *f* serve also to clamp and confine disks of wire cloth or perforated material, *m*, to the plates *c* over the inlet openings to the blower formed centrally through the disk plates *c*.

The hubs *h* are bored to receive the boxes *i*, which have formed thereon a portion of a spherical bearing, the followers *n* being screwed into the hubs *h*, against the spherical projections from boxes *i*, to prevent endwise movement of the boxes and to sustain them in position in which they have a capacity for universal motion to a small but sufficient extent to bring both boxes into line with each other.

The boxes *i* are provided with oil cups or reservoir *o*, and the sleeves or bushings *p*, fit at their ends in the boxes *i*, but the bodies of the bushings are made of less diameter than the bore of the boxes, so as to form between the boxes and the bushings annular chambers communicating with the oil cups *o*.

Along the length of the small part of the bushings *p* small holes are bored at intervals, and are filled with plugs, *q*, of leather or other suitable porous material, through which the oil filters as it percolates through the plugs in obtaining access to the journals *j*. I prefer to nut-thread said holes so that the plugs *q* can be screwed and fixed therein.

The fan-wheel shaft is prevented from having endplay by adjustment of the screws *r* in the ends of the bushings *p*.

On the shaft *b* are two hubs, arms from which sustain rings *s*, which are angular in cross-section. To one flange of each ring is united a disk, *t*, and the peripheries of the disks *t* are united by a belt or band, *u*, of perforated metal. The other flanges of the rings *s* abut against the inner surfaces of the side plates *c*, so that all the air passing through the screens *m* *m*, enters the fan-wheel, which revolves freely in the chamber made by the side plates *c* and delivers said air into the scroll-pipe of the case.

The fan blades *v* are attached to the housings *t* *u* *v*, and are braced by arms proceeding from a central hub or shaft, *b*.

I claim a blower case made with a scroll or spiral air-passage beginning and ending on parallel planes which are square or at right angles with the axis of the blast-wheel shaft and open to receive air from the fan-wheel and to conduct it through a constantly-increasing passage to the outlet for the blower.

Also, the blast-wheel made with a flat perforated shrouded ring *u* uniting the side shroudings *t* *t*.

Also, the arrangement, with the described volute blower-case of side plates *c*, with circular joint edges.

Also, the arrangement, with a fan-wheel, having

its peripheral shrouding reticulated or perforated, of screens *m*, for the purpose described.

Also, the arms *g*, which support the hub *h*, uniting by a ring fitting into the groove in the side of the blower for adjusting the arms with reference to the belt.

Also, the screw-threaded holes in the bushings *p*, combined with plugs or fillings of leather screwed therein.

Also, the improved blower, consisting of the peculiar scroll-shaped case, provided with screened side openings and containing a fan-wheel having a perforated peripheral shrouding so mounted as to be freely rotated within the case.

Also, a blower-case made up of dishing side plate as shown, to give side chamber room for the blast-wheel, surrounded by a scroll-shaped chamber which receives and conveys the air from the blast-wheel when made circular in planes which are radial from the center of the blast-wheel.

B. F. STURTEVANT.
